UNITED STATES PATENT OFFICE.

NORBERT METZ, OF DÜDELINGEN, LUXEMBURG.

ART. OF ROLLING.

1,229,497.

Specification of Letters Patent. Patented June 12, 1917.

Application filed October 3, 1916. Serial No. 123,602.

To all whom it may concern:

Be it known that I, NORBERT METZ, metallurgist, a subject of the Great Duchess of Luxemburg, residing in Düdelingen, Great 5 Duchy of Luxemburg, have invented new and useful Improvements in the Art of Rolling, of which the following is a specification.

This invention relates to a universal rolling mill which enables me to complete the 10 rolling of I-beams by means of one single set of rolls arranged in one single frame and consisting of two horizontal and two vertical rolls. With the said two horizontal rolls 15 four ring-shaped auxiliary rolls or collars are connected which when laterally displaced project into circular grooves or recesses in the front faces of the vertical rolls. In this manner I may attain that (1) the 20 web faces, the interior faces and the edges of the flanges can be operated upon when all the four auxiliary rolls join the horizontal rolls; (2) the web faces and the interior and exterior faces of the flanges can 25 be operated upon when all the four auxiliary rolls are separated from the horizontal rolls.

The invention is illustrated in the accompanying drawings, of which—

Figure 1 is a front view of the rolling 30 mill,

Fig. 2 is a side view of the same,

Figs. 3, 4 and 5 show the horizontal, vertical and auxiliary rolls in different positions,

35 Figs. 6 and 7 show, on an enlarged scale, the rolls in two different positions with a modified form of the auxiliary rolls or collars.

In all the figures *a* represents the horizontal 40 rolls, *b* the vertical rolls and *c* the auxiliary rolls or collars. The driving mechanisms for operating the rolls are marked *d*, *e* and *f*. In the example illustrated by the drawings electromotors provided with 45 worm and wheel gearing are employed. The upper roll is balanced in the known manner.

The rolling process shall now be explained referring to Figs. 3 to 7.

50 After the suitably pre-profiled bar to be rolled has at first been treated, be it simultaneously or subsequently, only with the horizontal rolls *a* and vertical rolls *b* the collars *c* resting on the rolls are as soon

as the flange has attained the sufficient 55 width, pushed forward so that the edges of the flanges can be operated upon, *i. e.* the two upper and the two lower collars are alternately advanced, the collars not in operation projecting into the corresponding 60 recesses of the vertical rolls *b*, as shown in Figs. 3 and 4.

Of course it is also possible to operate upon the flange edges at the same time with all the four collars if desired, as shown 65 in Fig. 1.

In Fig. 5 I have shown in what manner in the finish the collars are removed and the flanges are smoothed and straightened 70 by means of the vertical rolls.

To avoid the formation of sharp edges on the flanges at the point where the collars touch the horizontal rolls, I may modify the collars in such a manner that they do not only cover the flange edge but also 75 partially the inner face of the flange.

Fig. 6 shows one of the collars of this modified form in cross section operating together with the horizontal rolls *a*. As is seen, a sort of flange *g* of the collars *c* 80 overlaps the conical parts of the horizontal rolls, whereby the flanges of the beam are compressed and bent outwardly.

In Fig. 7 I have shown the manner in which the beam flanges are again set straight 85 in a subsequent operation by means of the vertical rolls *b*.

The same form of collars is also applicable when the beams, as shown in Figs. 3 and 4, are simultaneously operated upon 90 by the horizontal rolls, the vertical rolls and at one side by the collars. In this case it is necessary to make the flanges *g* of the collars *c* end with a sharp edge in order to avoid the formation of undesired edges 95 on the inside of the beam flanges.

Having now fully described and ascertained the nature of my invention, what I claim as new, and desire to secure by Letters Patent is:

1. In a rolling mill for rolling I-beams, the combination in one single frame of two horizontal rolls rotatable in vertical direction and two vertical rolls rotatable in horizontal direction with rolling collars slidable 105 on the shafts of the horizontal rolls and projecting into circular recesses in the faces of the vertical rolls.

2. In a rolling mill for rolling I-beams, the combination in one single frame of two horizontal rolls rotatable in vertical direction and two vertical rolls rotatable in horizontal direction with rolling collars slideable on the shafts of the horizontal rolls and projecting into circular recesses in the faces of the vertical rolls, the said collars being

provided with flanges adapted to partially overlap the horizontal rolls. 10

In testimony whereof I affix my signature in presence of two witnesses.

NORBERT METZ.

Witnesses:

Q. ZEUGEN,
S. THIES.
